US00D991605S

(12) **United States Design Patent** (10) **Patent No.:** **US D991,605 S**
(45) **Date of Patent:** **** Jul. 4, 2023**

(54) **CLEANING DEVICE**

(71) Applicant: **Murray Leonard Feick**, Kitchener (CA)

(72) Inventor: **Murray Leonard Feick**, Kitchener (CA)

(**) Term: **15 Years**

(21) Appl. No.: **29/836,279**

(22) Filed: **Apr. 26, 2022**

(51) LOC (14) Cl. **07-05**

(52) U.S. Cl.

USPC **D32/43**; D21/599; D21/808

(58) **Field of Classification Search**

(57) **CLAIM**

The ornamental design for a cleaning device, as shown and described.

DESCRIPTION

FIG. 1 is a front top perspective view of a cleaning device showing my design;

FIG. 2 is a front bottom perspective view thereof;

FIG. 3 is a top plan view thereof;

FIG. 4 is a bottom plan view thereof;

FIG. 5 is front elevation view thereof;

FIG. 6 is a rear elevation view thereof;

FIG. 7 is a right-side elevation view thereof; and,

FIG. 8 is a left-side elevation view thereof.

The portions of the cleaning device shown in broken lines form no part of the claimed design.

1 Claim, 6 Drawing Sheets
